(57) **CLAIM**

The ornamental design for an archwire, as shown and described herein.

DESCRIPTION

FIG. 1 is a front, right-side perspective view of an archwire; FIG. 2 is an enlarged partial view of FIG. 1; FIG. 3 is a front elevation view thereof; FIG. 4 is an enlarged partial view of FIG. 3; FIG. 5 is a rear elevation view thereof; FIG. 6 is an enlarged partial view of FIG. 5; FIG. 7 is a top plan view thereof; FIG. 8 is an enlarged partial view of FIG. 7; FIG. 9 is a bottom plan view thereof; FIG. 10 is an enlarged partial view of FIG. 9; FIG. 11 is a right-side elevation view thereof; and, FIG. 12 is a left-side elevation view thereof.

The dash-dash broken lines shown in the drawings represent portions of the archwire that form no part of the claimed design. The dot-dot-dash broken lines define the boundaries of the enlarged partial views and form no part of the claimed design.
